UNITED STATES PATENT OFFICE.

FRANK S. VERBECK, OF CHICAGO, ILLINOIS.

DESIGN FOR A LAMP-PEDESTAL.

No. 39,566.

Specification for Design.

Patented Sept. 22, 1908.

Application filed January 25, 1908. Serial No. 412,679. Term of patent 7 years.

To all whom it may concern:

Be it known that I, FRANK S. VERBECK, a citizen of the United States, residing at Chicago, in the county of Cook and State of Illinois, have invented a new, original, and ornamental Design for Lamp-Pedestals, of which the following is a specification, reference being had to the accompanying drawing, forming a part thereof.

The figure of the drawing is a perspective view of a lamp pedestal embodying my novel design, and it will be noted that my pedestal comprises a base made up of two

steps or leaves, a tapered column or standard and a cap mounted upon the standard. The lower end of the standard is larger than the upper end thereof and the cap is larger than the upper end of the standard.

I claim:

The ornamental design for a lamp pedestal, herein shown and described.
